No. 820,831.

PATENTED MAY 15, 1906.

C. A. STRUVE.
BALING PRESS.
APPLICATION FILED JULY 2, 1903.

UNITED STATES PATENT OFFICE.

CLEMENS A. STRUVE, OF FAYETTEVILLE, TEXAS.

BALING-PRESS.

No. 820,831.

Specification of Letters Patent.

Patented May 15, 1906.

Application filed July 2, 1903. Serial No. 164,059.

To all whom it may concern:

Be it known that I, CLEMENS A. STRUVE, a citizen of the United States, residing at Fayetteville, in the county of Fayette and State 5 of Texas, have invented certain new and useful Improvements in Baling-Presses; and I do hereby declare the following to be a full, clear, and exact description of the invention, such as will enable others skilled in the art to 10 which it appertains to make and use the same.

This invention relates to improvements in baling-presses.

The object of the invention is to provide 15 means whereby the plunger is returned to its normal position without providing a spring assembled therewith for this purpose.

Another object of the invention is the construction of a press provided with a sweep 20 for actuating the plunger, and said sweep carrying improved bearings, as is hereinafter fully described.

Still another object of the invention is the production of a press carrying means for 25 turning or pressing the edges of the bale being formed within the box, and said means simultaneously actuated with the other mechanism of said press.

With these objects and others in view the 30 invention consists in a press provided with a suitable frame and a plunger mounted thereon, said plunger actuated by means of a sweep comprising a tongue and a bar extending at right angles thereto, said bar provided 35 with rectangular bearings pivotally secured thereto.

The invention further consists in the mounting upon the frame of the press of a lever simultaneously actuated by the sweep 40 for returning the plunger to its normal position when the said press is in operation.

The invention further consists in the providing of a tucker or packing means which is simultaneously actuated by the plunger and the sweep and which is adapted to turn in or 45 compress the loose edges of the bale as it is formed within the box.

The invention further consists in the novel construction and arrangement of parts, as is 50 hereinafter fully described, illustrated in the accompanying drawings, and more particularly pointed out in the claims hereto appended.

In the drawings, Figure 1 is a top plan 55 view of the press constructed in conformance

with my invention, and Fig. 2 is a longitudinal side elevation of the same. Fig. 3 is a fragmentary plan view of a modified form of the invention. Fig. 4 is a fragmentary perspective view of the press. Fig. 5 is an enlarged 60 detail view of the tucker mechanism.

Like numerals of reference designate corresponding parts throughout all the figures of the drawings.

In the drawings, reference-numeral 1 indicates a suitable frame upon which is mounted a box 2 and a plunger 4, which is provided with a head 5, having an angular extension 6 formed integral therewith. Mounted upon a rigid bracket or bar 7 is a sweep 8, 65 comprising a tongue 9, rigidly secured by suitable means to a bar or member 10, which is pivotally mounted at 11 to the said bracket or bar 7. Rotatively mounted by suitable means, as at 12, are rectangular bearings 13. 70 Blocks 14 are retained upon the frame 1 and provide in conjunction with the cross-bar 15 means for retaining the plunger 4 in an assembled position with the other mechanism 75 of the press. 80

Pivotally secured to the frame 1 and adjacent to the plunger is a guide, which comprises in its construction a pivoted bracket or block 16, provided with a flat head portion 17 and a lug or extension 18, formed integral with the said block 16, projecting at right angles to the said portion 17. The said block, as heretofore stated, is pivotally secured to the frame and is adapted to be simultaneously actuated by the plunger 4, and 85 the head or flat portion 17 is adapted to coact in a horizontal position with the like portion 19 of the plunger 4 when the said plunger is at its farthest position on an inward stroke. Secured to the said bracket or block 16 is a 90 curved arm 20. Mounted upon the plunger 4 is a pin or bearing 21, which is adapted to engage the arm 20 of the block 16 and return said block to its normal position after the said plunger has been returned to its outward 95 position. Pivotally mounted upon the frame 1 is a lever 22, provided with a series of apertures 23. The said lever 22 is provided with a right-angular shoulder 24, or, if it is desired, the shoulder may be formed with a detachable plate and rigidly secured to the lever 22. The rod 25, pivotally secured to the plunger 4 at 26, is adjustably mounted upon the lever 22, and this rod is adapted to be retained in 100 an assembled position upon the said lever 22 105

110

and the plunger 4 by bolts or like means. When the press is in operation, the sweep is rotated, and as the bar 10 comes in contact, by means of the rectangular bearings 13, 5 with the angle-plate or shoulder 24 of the lever 22 the said lever 22 is moved into its outer position, and thereby actuating the rod 25 and withdrawing or extracting the plunger 4 from its inward or farthest position 10 within the box 2. It will be seen by this construction I do not employ a spring or similar means and still provide a positive construction for actuating the plunger 4. In so far as returning the said plunger to its outward 15 position. As the sweep is moved the rectangular bearings, as aforesaid, will engage the lever 22 in the recess formed upon its angular shoulder 24 and passing beyond said shoulder will come into contact with the flat 20 surface 19 of the plunger 4, and as the pressure is continued upon the tongue 9 and the bar 10 the plunger will be forced inwardly, and when it is at its farthest inward position 25 the flat surface 19 and the corresponding surface 17 of the bracket or block 16 will be in alignment, and as the rectangular bearing passes along the flat surface 19 of the plunger 4 it will come into contact with the surface 17 of the pivoted bracket or arm 16, and 30 before the plunger 4 is permitted to return to its outer position by the actuation of the lever 22 the rectangular block will pass upon the flat surface 17 of the bracket 16 and will be entirely removed from the path of the 35 plunger 4, and as the sweep is rotated the pivoted arm or bracket will permit of the rectangular bearing to pass over its head or surface 17 and the extension 18, and as the plunger 4 is returned by the mechanism here- 40 tofore described to its normal outward position the bent arm 20 will come into contact with the pin on the plunger, and the said bracket 16 will be forced into contact with the plunger 4 and retained there until the rectangular bearing comes in contact and moves 45 the same out of the said position.

I have found by practical experience that in all cylindrical or other bearings which are now on the market in passing over the 50 head of the plunger the said bearings as they perform this function are adapted to be nearly forced out of the path of the said member when they are beyond the center of their pivotable point, and this will cause the 55 forcing of the sweep or tongue forward, and a jar or shock is imparted to the horse or horses. A further defect is that the plunger will crush these bearings quickly when a force is placed 60 upon the same, and to overcome this defect I have found that providing a bracket adjacent to the lowest or innermost movement of the head of said plunger this bracket will receive the rectangular bearing and will not 65 permit of the same to be rotated, but will prevent the plunger from returning to its

outward position until the said bearing is entirely removed from the plane of the stroke of said plunger.

In the modification Fig. 3 a stationary bracket 27 is secured to the frame 1, and said bracket is adapted to receive the rectangular bearing 13 when the same has passed over the head of the plunger 4. In this modification the bracket 27 prevents the bearing from rotating when the same is partially removed 70 and in contact with the head of the plunger. As heretofore explained, the said bearing must be entirely removed by the actuation of the sweep before the plunger is permitted to slide into its outward position upon the 75 press. The cross-bar 15' is secured at one end to the fixed bracket 27 and extends diagonally across the plunger 4 and is secured to a cross-piece of the frame near the opposite end thereof. In this modification the sweep 80 is intended to be rotated in a direction opposite the direction of rotation in the preferred 85 form, as illustrated.

As shown in Figs. 1 and 2, a tucker or mechanism for forcing the edge of the bale 90 inwardly after each stroke of the plunger is employed. This mechanism is provided upon the said frame for the purpose of producing a bale not having ragged or loose material extending beyond the width of said 95 bale.

The operation and construction of the tucker device are as follows:

An arm or plate 28, which conforms in 100 shape to the feed-opening, is pivotally mounted upon the box 1 and is provided with an arm 29, extending outside of said box. The arm 29 is provided with a crank-arm 30. A slot 30' is formed in arm 30. Pivotally secured at 31 to the box of the press is a crank 105 arm or lever 29^a, as shown in Fig. 2. Said lever 29^a is provided with an extension extending at right angles to the main portion of the same and at its lowest extremity is pivotally secured to a rod 32. The lever 29^a is provided with a pin 31", which is positioned 110 within the slot 30' of the crank-arm 30. The rod 32 is secured to the plunger 4 at 33. The arm 29^a is provided with an extension projecting at right angles therefrom, said extension 115 engaging the slotted portion of crank-arm 30. When the plunger is at its outward position, the approximately U-shaped arm 28 of the tucker mechanism is extending inwardly into the box 2. When the said plunger is forced into the box, the rod 32 moves the lever-arm 29^a and through the medium of the pin 31" lifts the crank-arm 30, and thereby releases the tucker from engagement with the material which is being compressed within 120 the box 2. It will be seen that by the construction of this lever-arm and the crank-arm of the tucker-bar there is permitted a slight independent movement of the different parts although the interlocking crank-arms are 125 130

normally connected by means of the extension formed upon arm 29^a engaging the slotted portion of arm 30; but before the plunger has reached its outer position the said lever 5 arm will force the tucker down into the said box 2 of the press. This movement is simultaneous with the action of the plunger, and as the hay is pressed into the box 2 of the press the plunger will force the same into the 10 bale upon its inward stroke.

The advantage in the construction of my invention lies in the fact that the mechanism for returning the plunger to its outward position prevents the same from being actuated 15 by the material which is adapted to be pressed within box 2. It may happen that a foreign object is placed within the box, and if a spring for returning the plunger were employed the said plunger would be returned 20 to an outward position before the mechanism of the press is in position for this operation. The rectangular bearings prevent the plunger from returning to an outward position before the said bearings are entirely moved from the 25 path of the said plunger and insure the positive actuation of the device and also prevent the forcing of the sweep too quickly out of position, as is common with the ordinary bearings employed upon baling-presses now in use. 30 The mechanism for forcing the material for forming the bale without the usual ragged or loose condition, as heretofore experienced, is operated upon each actuation of the 35 plunger, the material which is forced into the bale by the stroke, the edges of such material is turned into the portion of the bale and, as heretofore stated, insures a compact and even surface.

Although I have shown in the accompanying drawings and described in the specification the preferred forms of my invention, I reserve the right to make such modifications and changes in dimensions of the press as shall fairly fall within the scope of the invention.

Having thus fully described my invention, what I claim as new, and desire to secure by Letters Patent, is—

1. In a baling-press, the combination with 50 a frame and a box mounted thereon, a plunger slidably secured upon said frame, a sweep pivotally secured to said frame and carrying rotatable rectangular bearings, and means upon the frame for engaging the said bearings when they pass off of the plunger-head to prevent the bearings from rotating.

2. In a baling-press, the combination with 55 a frame and a plunger mounted thereon, a sweep provided with rotatable rectangular bearings adapted to actuate said plunger, and means upon said frame for engaging the bearings to prevent the plunger from returning to its normal position until the said bearings are out of the path of the plunger.

3. In a baling-press, the combination with

a frame, a cross-head and a plunger mounted thereon, of a guide mounted upon said frame and coacting with said plunger to prevent the return movement of said plunger before said cross-head is positively out of the line of 70 the stroke of said plunger.

4. In a baling-press, the combination with 75 a frame and a box thereon, of a plunger mounted upon said frame, a sweep provided with bearings pivotally secured to the frame, said bearings carried by the sweep adapted to engage said plunger, a pivoted bracket secured to the frame and adapted to receive the bearings engaging the plunger when the same is in its innermost position within the 80 box, a tucker mounted upon the box, and means for actuating the said tucker and operating the several parts of the press.

5. In a baling-press, the combination with 85 a frame, of a box thereon and a plunger secured upon said frame, a sweep pivotally mounted upon the frame and provided with rectangular bearings, a pivoted bracket secured to said frame and provided with a head which is adapted to coact with the head 90 of the plunger when the same is at its inward stroke, an arm secured upon said bracket and means carried by the plunger for returning the bracket to its coacting position when the plunger is actuated.

6. A baling-press comprising a frame and 95 a box thereon, a sweep provided with rotatable rectangular bearings mounted upon said frame, a plunger slidably secured upon said frame, means for returning the plunger to its 100 outward position, means for pressing inwardly one of the edges of a bale and means carried upon the frame for receiving said rectangular bearings carried by the sweep to prevent the kick of the plunger.

7. In a baling-press, the combination with 105 a frame and a box thereon, of a plunger slidably secured to said frame, a bracket movably mounted upon the frame comprising a head and an extension formed integral therewith, a curved arm secured to said bracket, means carried by a sweep pivotally mounted upon the frame for engaging and actuating the plunger, said plunger provided with means engaging the curved arm secured to 110 the bracket for imparting movement thereto.

8. In a baling-press, the combination with 115 a frame and a box thereon, of a plunger mounted upon said frame, a mechanism for returning the plunger to its outward position comprising a lever pivotally secured to the frame and a shoulder formed integral with said lever and means connecting the lever with the plunger, a tucker mounted upon said box and provided with means connected with the 120 plunger for actuating the same, and means upon said frame for operating the lever and the plunger.

9. In a baling-press, the combination with 125 a frame and a box thereon, of a sliding plun-

ger mounted upon the frame, a lever mechanism for returning the plunger to its outward position, a tucker mechanism pivotally mounted upon the box, and means carried upon the frame for alternately actuating the plunger and the tucker mechanism.

10. In a baling-press, the combination with a frame and a box, of a plunger carried by said frame, means upon the frame and in alignment with the head of the plunger when the same is at its innermost stroke, and means carried by said frame for engaging the head of the plunger and the means upon the frame for preventing a kick of the plunger and insuring the entire removal of the same from the path of the stroke of the plunger.

11. In a baling-press, the combination with a frame, a box and a plunger thereon, a

sweep pivotally mounted upon said frame, means upon the frame for returning the plunger to its outward position, a pivoted bracket mounted upon the frame, means upon the sweep for engaging the head of the plunger and the head of said pivoted bracket, said bracket secured upon the frame in a parallel position to the plunger, a tucker pivotally mounted upon the box and provided with means secured to the plunger for simultaneously actuating the same.

In testimony whereof I hereunto affix my signature in presence of two witnesses.

CLEMENS A. STRUVE.
